SUPPORTING CLAMP FOR A ROPE SIDE FRAME CONVEYOR

Roy F. Lo Presti, Chicago, Ill., assignor to Goodman Manufacturing Company, Chicago, Ill., a corporation of Illinois

Filed June 23, 1958, Ser. No. 743,600

3 Claims. (Cl. 24—126)

This invention relates to rope frame conveyors of the type generally disclosed in Gleeson Patent No. 2,907,448 (one rope frame); Craggs and McCann Patent No. 2,773,257 (two rope frames); and Lo Presti Patent No. 2,833,395 (more than two rope frames); and particularly to an improved clamp for locking a troughing idler assembly to a rope frame, and for locking a rope frame to a supporting stand.

Conventional rope clamps distort, flatten and do varying amounts of damage to the rope and in spite of this many of them do not hold well.

Accordingly, an important object of the present invention is to provide a rope frame conveyor having a rope clamp which is easily and quickly attached or released yet which holds tight without damaging the rope. In one preferred embodiment, this is carried out by a tapered screw, crossing and engaging the rope obliquely and which can be tightened by rotating to cam it into intimate, meshing, interengagement between the screw threads and the rope strands. One feature of the invention provides for the root only of the screw thread to bear against the clamp to avoid damage to the clamp by the tips of the threads. Another feature, particularly useful where a stranded rope is used, is a coarse thread approximating the pitch of the rope so that individual rope strands will be readily gripped between adjacent screw threads without damaging the rope. In some cases a non-stranded rope may be employed.

Other objects and advantages will be developed in the following description taken in connection with the drawing in which:

Figure 1 is a fragmentary cross sectional view of the load-carrying reach of a rope sideframe conveyor employing a pair of troughing idler assembly clamps illustrating one preferred embodiment of the present invention;

Figure 2 is an enlarged side view of Figure 1 taken in the direction of the arrows 2—2;

Figure 3 is an enlarged cross sectional view of Figure 2 taken along line 3—3;

Figure 4 is a view similar to Figure 3, showing an alternate form of locking screw;

Figure 5 is a diagrammatic view of Figure 3 taken along the line 5—5 illustrating the intermeshing effect between the screw threads and the rope strands; and

Figure 6 is an alternate application, showing the improved rope clamp applied to the top of a rope supporting stand.

Like parts are referred to by like reference characters throughout the figures of the drawing.

Referring more particularly to the drawing, a pair of flexible sideframes, comprising stranded wire ropes 11, 11, are trained along a course in the manner described for example in Patent No. 2,773,257. A flexible troughing idler assembly 12 carries the upper or load-carrying reach 14 of a conveyor belt. The return reach and certain other parts of a complete conveyor are not shown

here as they are unnecessary in the description of the present invention.

The ropes 11, 11 may be held at a desired height by stands placed at intervals therealong. One of these stands 5 is shown fragmentarily in Figure 6 and consists of a pair (only one shown) of upstanding legs 14 on feet 16, held apart by a spreader bar 17. A rope clamp according to the present invention and generally designated 18 is mounted atop each leg 14 and will be described in more 10 detail presently.

Now, returning to the troughing idler assembly 12, it is here shown as of the fully flexible type and comprises a center, load-carrying, training roller 19, flanked by a pair of wing rollers 21, 21, all being rotatable on dead 15 shafts 22, 22, 22. The shafts are interconnected between rollers by pairs of links 23 connected by pivot pins 24, 26 carried by the ends of the shafts. As best shown in Figure 3, each end shaft is connected by a similar pair of links 27, 27 to a clamp generally designated 28. The 20 links are held by pins 29, 31. Washers 32, 32 serve as spacers or fillers on the top and bottom surfaces of the clamp body 33.

Now, referring specifically to the improved clamp 28, shown in Figure 3, it comprises a U-shaped body or plate, 25 already designated 33 and made up of a limb 34 connected to pin 31, a lower limb 36, both limbs being joined by a rope-embracing bight 37. Limb 34 is provided with an aperture, generally circular in this case, and designated 38a. A mating aperture 38 is provided 30 in the other limb. A lock screw 39 is formed with a coarse thread 41. It will be observed that this is a substantially cylindrical thread, that is the outer tip of the thread may be described as lying substantially in a cylindrical surface so that the radius of the thread periphery, 35 as measured from the central axis of the screw body, is substantially uniform; this enables the screw to fit snugly, with reasonable operating tolerances, within the apertures 38, 38a. In contrast to the thread periphery, the root 42 is tapered, tapering downward in diameter from 40 the eye portion 43 at the top end of the screw; this taper provides the desired squeezing effect on the rope when tightened.

Figure 3 shows how the coarse portions of the thread 45 straddle one of the rope strands 44 to hold them positively intermeshed. This is further illustrated, schematically, in Figure 5. The eye portion 43 provides a convenient coupling for any one of a variety of available tools such as a screw driver, plier handle or spike and enables an extremely high force to be applied, causing 50 the tapered root 42 to cam the rope forcibly outward into positive locking engagement between the screw and the bight.

It will be apparent that since the screw thread pitch P is coarse, roughly approximating at least the pitch PP of the rope, the screw threads and rope strands will effectively intermesh without damage to either.

Figure 4 illustrates a modified form of clamp which 55 may be identical to the one shown in Figure 3 except that a different lock screw 46 may be employed. In this case the screw is formed with a full taper, that is both the periphery of the thread 47 and the root 48 are tapered. Note that the pitch P of the screw thread in Figure 4 is preferably made greater than the thickness T of the clamp body; thus, the root of the screw will bear directly on the walls of the apertures 38 and 38a 60 within the limbs, keeping the thread tip entirely clear of bearing engagement with the clamp, thereby preventing damage to the thread by engagement with the limbs, and vice versa. Note that in Figure 4, the thread tip bears only against the rope itself. This construction enables the use of a relatively fragile, thin thread, easily able to 65 slip between adjacent rope strands 44, 44. As seen in 70

Figure 5, it will be observed that the angle of the screw thread can be made to approximately correspond with the angle of the rope strands at the point of contact.

The clamp 18 (Fig. 6) may be substantially the same as clamp 28, comprising namely a long limb 49 welded atop the foot 14, a short limb 51 and a connecting bight 52. In the present case a lock screw 46 is shown extending through apertures in the limbs and holding the rope firmly in place. If desired, the alternate lock screw 39 might be used.

While the invention has been described in terms of a number of arrangements and forms, the scope thereof is intended to be limited only by the claims here appended.

I claim as my invention:

1. A clamping device for supporting a conveyor component from a flexible strand of a flexible strand side-frame conveyor assembly, said clamping device including a U-shaped body member defined by a pair of limb portions each having an aperture therethrough and a bight portion connecting the limb portions together, means for connecting one of the limb portions to such conveyor component, and an elongated externally threaded screwlike member disposed within the apertures adapted to wedge such strand against the bight portion, said screwlike member having a tapered root portion disposed intermediate adjacent threads for engaging such strand to so wedge same against the bight portion of the body member, said adjacent threads having a pitch that is wider than the thickness of the limb portions of the body member to enable the root portion of the screw-like member to directly engage the limb portions of the body member.

2. The clamping device as set forth in claim 1 wherein the thread of the screwlike member has a tapered outer periphery.

3. In a flexible strand sideframe conveyor apparatus having at least one flexible strand means trained along

a given course, said strand means comprising a plurality of twisted strands having a pitch corresponding to the circumference divided by the number of external strands, the improvement comprising, in combination with the strand means, a clamping device for securing a conveyor component to the strand means, said clamping device including a U-shaped body member defined by a pair of limb portions each having an aperture therethrough and a bight portion connecting the limb portions together, means for connecting one of the limb portions to such conveyor component, and an elongated externally threaded screwlike member extending through the apertures and disposed therein in direct contact with the limb portions and the strand means to wedge the strand means forceably into the bight portion of the body member, said screwlike member having a substantially cylindrical outer thread periphery and a tapered root portion disposed intermediate adjacent threads with the outer periphery of the thread directly engaging the limb portions of the body member and the root portion directly engaging the external strands of the strand means with an individual external strand thereof being gripped between adjacent threads of the screwlike member, the thread of said screwlike member having a pitch substantially equal to the pitch of the twisted strands of the strand means, to enable the external strands of the strand means and the adjacent threads of the screwlike member to intermesh without appreciable damage to either the thread of the screwlike member or the strands of the strand means.
